FIG. 3.

FIG. 4.

FIG. 5.

FIG. 6.

FIGURE 1 is a front elevational view of a lifting clamp embodying my new design;

FIGURE 2 is a right side elevational view thereof;

FIGURE 3 is a rear elevational view thereof;

FIGURE 4 is a left side elevational view thereof;

FIGURE 5 is a top plan view thereof; and

FIGURE 6 is a bottom plan view thereof.

The dominant features of the claim are shown in the drawing in full lines, said features being further characterized by the overall appearance of a uniformly sloped bottom edge, and raised side plates with side edges generally parallel to the sides of the lifting clamp, as best seen in FIGS. 1, 2 and 3.

I claim:

The ornamental design for a lifting clamp, as shown and described.
